UNITED STATES PATENT OFFICE.

HARRY KITHAS, OF FORT WORTH, TEXAS.

DESIGN FOR A CIGARETTE HOLDER.

Application filed April 26, 1926. Serial No. 17,457. Term of patent 7 years.

To all whom it may concern:

Be it known that I, HARRY KITHAS, a citizen of the United States, residing at Fort Worth, in the county of Tarrant and State of Texas, have invented a certain new, original, and ornamental Design for Cigarette Holders, of which the following is a specification, reference being had to the accompanying drawing, forming a part thereof.

Fig. 1 is a side elevation of a cigarette holder, showing my new design.

Fig. 2 is a plan view of the same.

I claim:

The ornamental design for a cigarette holder, as shown.

In testimony whereof, I set my hand, this 21st day of April, 1926.

HARRY KITHAS.
